J. E. LAPPEN

PROCESS OF AND APPARATUS FOR THE TREATMENT OF TOW

Filed Jan. 29, 1925.

Inventor
James E. Lappen
By his Attorneys
Michael Kilson

UNITED STATES PATENT OFFICE.

JAMES E. LAPPEN, OF CROOKSTON, MINNESOTA.

PROCESS OF AND APPARATUS FOR THE TREATMENT OF TOW.

Application filed January 29, 1925. Serial No. 5,617.

To all whom it may concern:

Be it known that I, JAMES E. LAPPEN, a citizen of the United States, residing at Crookston, in the county of Polk and State 5 of Minnesota, have invented certain new and useful Improvements in Processes of and Apparatus for the Treatment of Tow; and I do hereby declare the following to be a full, clear, and exact description of the 10 invention, such as will enable others skilled in the art to which it appertains to make and use the same.

My invention provides an improved process of and apparatus for the treatment of 15 tow and other fibrous materials with a germicide or insect-destroying fluid, such as sulfur dioxide vapors, and, generally stated, it consists of the novel treatment, devices and combination of devices here- 20 inafter described and defined in the claims.

The immediate and particular object of the invention has been to destroy bugs and various insects that are reproduced rapidly in tow and in articles and things made from 25 tow. One of the extensive uses of tow is in upholstering furniture, and it has been found that these bugs or insects will continue their reproduction after the tow has been incorporated as upholstering in furniture and the like. Of course, these bugs are seriously objectionable not only because 30 they leave the tow and crawl about the furniture in the room, but for the reason that they also damage the tow and the upholstering cloth. The tow used for upholstering and any other purposes must be kept dry, and hence it cannot be treated with any of 35 the bug-destroying or insecticidal liquids. Attempts have been made to destroy the 40 insect life in tow by subjecting the same, while in loose condition, to various insect-destroying gases, but the success of this treatment is only partial because the gas applied to the tow in loose condition will 45 remain commingled therewith but for a very short time and not for a sufficient length to destroy the larva, which, hatching later, produces further bug life in the tow or in the upholstering material.

I have found that, by subjecting the tow, while in loose condition, to a strong blast of 50 germ-destroying or insecticidal gases, such as sulfur dioxide fumes, and by then compressing the tow into very compact condition, such as pressed bales, while still thoroughly permeated with the strong gases, the

gases will be caused not only initially to act on the bugs and larvae with more destructive effect, but that the gases will be caged and caused to remain commingled to 60 a very considerable extent in the compact tow for a sufficient time either to complete the destruction of the larvae or to destroy the bugs or insects when hatched. The 65 hatching period of most of the bugs or insects found in tow is approximately from four to eight days, and I have found that much of the sulfur dioxide fumes will remain in the compressed or tightly baled tow for several weeks, sometimes as long as 70 thirty days. Thorough and extensive tests of this process have shown the most satisfactory results.

The process may be carried out by any 75 suitable apparatus, but preferably I employ an apparatus the main features of which are illustrated in the single view of drawing, which is a vertical longitudinal section, some parts being diagrammatically 80 indicated.

Of the parts of the apparatus illustrated, the numeral 1 indicates the cylinder and the numeral 2 the plunger of a tow press. The cylinder is provided with a receiving hopper 3 and with a detachable head 4. The 85 plunger 2 may be reciprocated by any suitable means, but, as shown, is connected by a long pitman 5 to a power-driven chain 6 that runs over sprockets 7. The numeral 8 indicates an endless conveyor that delivers the tow *y* to the hopper 3. The numeral 9 indicates a gas or vapor retort containing a suitable gas or vapor-producing material, such as sulfur *y'*, shown as held on a grate 90 10, through which air may be drawn in to support the combustion of the sulfur. The retort 9 is connected by a pipe 11 to a blower 12, the discharge spout of which is connected to a vapor delivery pipe 13 that terminates in a nozzle 14 located in the hopper 3 in position to discharge a blast of hot 95 sulfur dioxide fumes or vapor directly against and through the loose tow as it is being delivered into the cylinder and after 100 it has been delivered into the cylinder and 105 immediately before it is compressed. The tow delivered into the cylinder will be compressed by movement of the plunger 2 toward the head 4. The cylinder head 4 will 110 be detachably secured by suitable or well known means and, after the tow has been compressed in the cylinder in a very com-

pact form with the sulfur dioxide fumes
caged therein, the bales will be tied or se-
cured by wire applied in the well known or
any suitable manner.

5 It seems to be highly important that the
sulfur dioxide fumes be delivered into the
tow while still quite hot or very warm and,
hence, the retort is connected directly to the
10 point of discharge and the blower used to
hasten the delivery of the hot vapor or
sulfur dioxide gas.

What I claim is:

1. The process of treating fibrous mate-
rial for the destruction of bug and insect
15 life, which consists in permeating the tow
with an insecticidal gas while in loose con-
dition, and in compressing such fibrous ma-
terial into compact form while still perme-
ated with such gas.

20 2. The process of treating fibrous mate-
rial for the destruction of bug and insect
life, which consists in permeating the tow
with an insecticidal gas while in loose con-
dition, in compressing such fibrous mate-
25 rial into compact form while still perme-
ated with such gas, and baling the fibre thus
compressed in its compact condition.

3. The process of treating fibrous mate-
rial for the destruction of bug and insect
life, which consists in permeating the tow
with a hot insecticidal gas while in loose
condition, and in compressing such fibrous
material into compact form while still per-
meated with such gas.

4. The process of treating fibrous mate-
rial for the destruction of bug and insect
life, which consists in permeating the tow
with sulfur dioxide gas while in loose con-
dition, and in compressing such fibrous ma-
terial into compact form while still perme-
ated with such gas.

5. An apparatus for use in treating
fibrous material for the destruction of bug
and insect life, comprising a fibre press
having a receiving hopper, means for pro-
ducing an insecticidal gas, and means for
delivering such gas into the loose fibre
where it passes from the hopper to said
press and at the place where it is to be
compressed.

In testimony whereof I affix my signa-
ture.

JAMES E. LAPPEN.
